UNITED STATES PATENT OFFICE.

WINSLOW R. PARSONS, OF CHICAGO, ILLINOIS.

RUFFLING ATTACHMENT FOR SEWING-MACHINES.

SPECIFICATION forming part of Letters Patent No. 756,885, dated April 12, 1904.

Application filed November 10, 1902. Serial No. 130,642. (No model.)

To all whom it may concern:

Be it known that I, WINSLOW R. PARSONS, a citizen of the United States, residing at Chicago, in the county of Cook and State of Illinois, have invented certain new and useful Improvements in Ruffling Attachments for Sewing-Machines, of which the following is a full, clear, and exact specification.

My invention relates to ruffling attachments generally in which the pivoted and sliding parts of necessity require lubricating with oil to reduce the friction sufficiently to enable the ruffler to work at all accurately and with certainty.

My invention particularly relates to improvements in ruffling attachments for sewing-machines in which the attachment is rigidly secured to the presser-bar of the sewing-machine and a ruffling-blade actuated through the medium of a lever secured to the needle-bar thereof.

More specifically stated, my invention relates to the above class of rufflers in which the needle-bar lever above referred to and the lever to which the ruffling-blade is secured and from which it directly receives its motion are upon opposite sides of the standard of the ruffler-frame upon a pivot common to both and the lost motion of the ruffling-blade is regulated and adjusted to vary the width of the ruffle or plait by a contact device pivoted upon the needle-bar lever and adjustable between and with reference to two stops fixed upon the ruffling-blade lever—as exemplified, for example, in Letters Patent No. 354,577, granted me December 21, 1886, for "Ruffling attachments for sewing-machines."

My invention further relates to improvements in rufflers in which the foot-piece by which the ruffler is secured to the presser-bar is fixed to the frame of the ruffler and the spring presser-foot is secured at one end to the presser-piece, as exemplified in my Letters Patent above mentioned.

Prior to my invention a substantial number, if not all, of the rufflers upon the market have for their successful operation required the application of a lubricant for reducing the friction of the various parts of the ruffler

sufficiently to enable rufflers to work at all 50 accurately or with uniform certainty and also to reduce wear for the purposes of necessary durability, and this particularly at the pivot of the needle-bar and ruffling-blade and between the upper surfaces of the ruffling-blade 55 and plates or other devices suspended over it, at which points the friction and wear of the ruffler are the greatest, which use of oil, however, is not only seriously objectionable because the fabrics, and particularly fine and 60 expensive fabrics, to be ruffled are frequently irreparably injured by the oil, but because of the accumulation of dirt and dust upon the ruffler is hereby promoted to a degree requiring frequent cleaning and that further 65 cleaning is required owing to the spreading of the oil over the surface of the ruffler and the gumming of such surfaces and between the joints to which it is necessarily furnished.

Another serious objection to rufflers upon 70 the market prior to my invention is the necessity of employing an expert to adjust each ruffler to the individual machine upon which it is to be operated before the ordinary user and operator can produce a perfect ruffle or 75 plait. In other words, when a ruffler is adopted for a particular make and style of sewing-machine the custom is to then perfectly fit and adjust such a ruffler to a sample machine of that style and to thereafter make 80 all subsequent rufflers so closely follow the construction of this first ruffler that any of them when attached to that sample machine will produce perfect ruffles and plaits without 85 previously fitting or adjusting them thereto. Sewing-machines, however, made by the same 90 tools, dies, jigs, lathes, and templets differentiate the one from the other to a degree which requires and has always required their individual adjustment by an expert before 95 there is any assurance that they can be successfully operated by the ordinary user, which differences, among other things, include variations in the length of the up or down stroke, or both, of the needle-bar, in the tension, in the stroke of the feed, and not infrequently inaccurate fitting and adjustment of various parts of a machine, and the result is

that although every sewing-machine of a large number of the same style may after being so adjusted to do the same class and kind of stitching the fact remains that their movement is differentiated to a degree that a ruffler which has been accurately fitted and adjusted to one machine will not produce perfect ruffles or plaits upon the other until individually properly fitted and adjusted thereto, and to which can only be done by an expert.

Prior to my invention the adjustment of rufflers has been necessarily limited to a range of adjustment that not infrequently the variations in a sewing-machine are so great that 15 although the machine may be adjusted to do good sewing the ruffler cannot be adjusted thereto at all—as, for example, the length of stroke of the needle-bar may be so extended or so contracted or varying as to the point of 20 its termination on either its up or down stroke that the ruffling-blade will move too far forward or too far short of the point at which it must stop with reference to the shoulder of the presser-foot or the forward end of the separating-blade, or both, that the production of a 25 perfect ruffle or plait is impossible, for it is well understood that, allowing for the difference in the thickness of fabrics being ruffled, a perfect ruffle or plait cannot be produced 30 without the ruffling-blade in making a ruffle or plait carried the fold of the fabric of every ruffle up to and not beyond or short of the shoulder on the presser-foot, while at the same time the separating-blade must be opposite the same 35 point and neither beyond or short of it, all of which is equally true both in making full gathers, scant gathers, and narrow and wide plaits. All this is none the less true because a ruffler might be fitted and adjusted to the individual sewing-machine it accompanies and at 40 the time when the machine itself is adjusted, as is customary before delivering a sewing-machine to the ordinary user, for the fact remains that such an adjustment of a ruffler in 45 the practice of the sewing-machine trade is rarely, if ever, made, the practice being to furnish a sewing-machine with a box of attachments, including a ruffler designed for that particular style of sewing-machine taken at 50 random from a number of rufflers without even trying it upon the particular sewing-machine which it accompanies and, much more, without attempting to fit or adjust it thereto. Now while it is true that provision has heretofore been made for an adjustment of the 55 separator-blade with reference to the presser-foot and for the adjustment of the presser-foot relative to the separator-blade or the ruffling-blade no means have heretofore existed 60 for simultaneously adjusting the presser-foot and the separating-blade with reference to the ruffling-blade and needle-hole.

In practice the presser-bar is sometimes too large for the attachment of the ruffler, and, on 65 the other hand, it is sometimes so small that

when the ruffler is tightened thereon the ruffler, or for some other discrepancies in construction, is not in position for the necessary perfect registering of the needle with the needle-hole in the presser-piece, through which the needle must pass and in which it should center to properly stitch the ruffle or plait, and it is therefore obvious that the adjustment of a ruffling-blade alone toward and from the presser-foot cannot accomplish a perfect adjustment in the absence of an adjustment of the presser-foot. Again, if the upstroke of the needle-bar is higher than that for which the ruffler is adjusted the ruffling-blade will be moved past the shoulder of the foot, at about which point it must stop in order to produce a perfect ruffle or plait, and if, on the other hand, the upstroke of the needle-bar is shorter than that for which the ruffler is adjusted the forward stroke of the ruffling-blade will terminate before reaching said shoulder, and the result in both instances is an incomplete and imperfect ruffle or plait, as may be.

In view of the foregoing it will now be appreciated and understood that any means, and particularly such as are hereinafter described, by which the ordinary user of sewing-machines can readily, conveniently, and quickly perfectly fit and adjust a ruffler to a sewing-machine so as to produce perfect ruffles and plaits, and thereby dispense with the services of an expert, is an important and substantial improvement in the art of rufflers.

The prime object of my invention is to have a ruffler of such a construction that the use of oil and other lubricant is not only rendered entirely unnecessary, but by which the movements of the several parts of the ruffler are rendered free and accurate to a maximum degree and their friction reduced to a degree substantially promoting the durability of the ruffler, and this particularly as to those parts of the ruffler which owing to their position and relation are subject to greater friction than other parts and in which the presence of friction is most undesirable for the best results in operation and durability.

Another object of my invention is to produce a ruffler in which provision is made for increasing and diminishing the distance between the stops for the contact device by a movable stop adapted to increase the range of lost motion adjusted and regulated by the contact device, thereby increasing the length of the forward stroke of the ruffling-blade in an improved manner and producing such an adjustment of the ruffling-blade in its backward stroke as to result in the production of uniform and accurate ruffles and plaits to a degree impossible when there is no adjustment of the stops or either of them.

A further object is to reduce the friction of the upper surface of the ruffling-blade and the part or parts overlying it and by such means

75

as provide against the employment at any time of a lubricant and also to combine with the ruffling-blade a shifting ball-bearing fulcrum.

Another object of my invention is to provide for a simultaneously forward and backward adjustment of the presser-foot and the separating-blade with reference to the ruffling-blade and the needle-hole in the presser-piece.

A still further object is to provide for simultaneously adjusting both the presser-foot and the separating-blade by means enabling the ordinary operator of sewing-machines to perfectly adjust a ruffler to unavoidable variations either in the form or relative arrangement of the parts of sewing-machines of the same style to which a ruffler has been adapted, which variations have heretofore necessitated the services of a sewing-machine expert for the proper adjustment of a ruffler thereto, but which adjustment by my invention may be now done by the ordinary and average operator of a sewing-machine.

With these ends in view my invention consists in certain features of novelty in the construction, combination, and arrangement of parts by which the said object and certain other objects hereinafter appearing are attained, all as fully described with reference to the accompanying drawings, and more particularly

30 pointed out in the claims.

In the accompanying drawings, Figure 1 illustrates a side elevation of a ruffler embodying my invention in which the needle-bar lever is at the limit of its upward stroke and the ruffling-blade at the limit of its forward stroke, with dotted lines indicating the needle-bar lever in a position substantially between its upper and lower stroke and with the contact device in a different adjustment than that 40 shown in full lines. Fig. 2 is a similar view of the opposite side of the ruffler, in which the needle-bar lever and the ruffling-blade are in the same position as in Fig. 1, but with dotted lines indicating the needle-bar lever at the limit of its downward stroke and the ruffling-blade at the limit of its backward stroke.

Fig. 3 represents a top plan view of the ruffler; Fig. 4, a similar view on the line 44, Fig. 1; Fig. 5, the bottom plan view thereof 50 on the line 55, Fig. 1. Fig. 6 is a top plan view of the blank from which the frame-plate of the ruffler is subsequently completed by upwardly bending the foot-piece and the standard or upright at a right angle to the bed portion of the frame. Fig. 7 is a rear end elevation of the ruffler; Fig. 8, a front end elevation of the same; Fig. 9, a detail transverse section through the bed-plate and the ruffling-blade carrier on the line 99, Fig. 3, particularly showing the ball-bearing between the ruffling-blade carrier and the slotted guide therefor of the ruffler-frame and also the manner of mounting on the ruffler-frame of the adjustable sliding plate to which the separating-blade and presser-foot are secured, to-

gether with the eccentric for adjusting same. Fig. 10 is a detail longitudinal section of the same, but further including the separating-blade, the ruffling-blade, the presser-piece, the strip-guide thereon, and the presser-foot; Fig. 11, a detail perspective of a modified form of the presser-piece bent to position and form and a portion of the ruffler-frame; Fig. 12, an enlarged bottom plan view of the ruffling-blade, showing a means for removably attaching it to its carrier with the ruffling-blade shown locked thereto. Fig. 13 is a similar view showing the ruffling-blade in position for removal from its carrier. Fig. 14 is a vertical section on the line 14 of Fig. 2, illustrating in detail the construction providing for ball-bearings between the upright of the ruffler-frame and the needle-bar lever and ruffling-blade lever; Fig. 15, a side elevation of the upright and the needle-bar lever with the ruffling-blade lever removed; Fig. 16, a detail elevation of one of the perforated plates or washers for holding the antifriction-balls of the needle-bar lever and the ruffling-blade; Fig. 17, a section through the same on the line 1717, Fig. 16.

Similar numerals of reference indicate the same parts in the several figures of the drawings.

In the blank shown in Fig. 6, 1 indicates 95 the bed-plate of the ruffler-frame; 2, the upright or standard thereof; 3, the presser-piece by which the ruffler is attached to the presser-foot of a sewing-machine, and 4 the ruffling-blade guide-plate. In the finished ruffler-frame the upright 2 is bent upwardly at a right angle to the bed-plate 1 of the ruffler-frame, as indicated, for example, in Figs. 7 and 8, and the presser-piece is bent upward also at about a right angle, as indicated, for instance, in Figs. 100 1, 2, and 10, and the ruffling-blade guide may also have a slightly-upward bend, as indicated in Fig. 9, to bring it in a desired position in reference to the ruffling-blade carrier for the purposes of a ball-bearing, as hereinafter described.

Pivoted to the upright 2 on a pivot 5 (see Fig. 7) is the needle-bar lever 6, provided at its outer end with a fork 7 or any other desired formation for attachment to the needle-bar of a sewing-machine, and on the same pivot on the opposite side of the upright is the ruffling-blade lever 8, or, in other words, the needle-bar lever 6 and the ruffling-blade lever 8 are respectively pivoted on opposite sides 105 of the upright on a pivot common to both.

On opposite sides of the upright 2 and centered on the pivot 5 are disks or plates 9 and 10, respectively, provided with a central perforation 11, by which they are sleeved on the pivot 5, which said disks are provided with perforations 12 (see Fig. 16) of a diameter slightly larger than that of antifriction-balls 13, resting in the perforations and confined therein and bearing against the upright 2, the 110 120 130

needle-bar, and ruffling-blade levers, respectively, to which end both of said levers are provided, respectively, with opposing annular grooves 14 15, receiving said balls, and 5 preferably formed by bending the metal of which said levers are composed. The purpose of the perforations 12 to receive the balls is to maintain them separated from each other and also permanently at equally-distant points 10 with reference to their bearing against the levers, and, too, by the use of a minimum number of balls reducing the friction and wear of the levers to a degree rendering the employment of a lubricant entirely unnecessary and 15 also to reduce the cost of employing ball-bearings in a ruffler to a minimum and to a commercial basis, enabling the manufacturer to enter into competition with rufflers now on the market in which any such bearings are absent. 20 In this connection it is proper to add that it would not be practicable from a commercial standpoint to employ ball-bearings for the needle-bar lever and ruffling-blade lever if the annular grooves had to be entirely filled with 25 balls, because the cost of such a number of balls would increase the cost of the ruffler to a sum substantially destroying its sale in competition with rufflers not having ball-bearings, and therefore the result accomplished by employment of ball-bearings in rufflers would be defeated commercially if their number is not correspondingly reduced, and if at the same time the reduced number are not maintained against 30 running together in the annular grooves which should be in said lever to receive such balls. 35 It may also be remarked that the advantage to be gained by the employment of ball-bearings in rufflers, and particularly for the pivotal points of the needle-bar lever and ruffling- 40 blade lever where the friction, wear, and strain in a ruffler is the greatest, has long been recognized as extremely desirable for the perfect operation of a ruffler and for avoiding the employment of a lubricant, 45 owing to the impossibility of using a lubricant without frequently injuring the goods being ruffled, to say nothing of the annoyance and time required to apply it and cleaning of the ruffler after the application of the lubricant; 50 but so far no one before my invention has discovered how to attach ball-bearings to a ruffler in a manner eliminating the objectionable cost before referred to, and this, no doubt, because of the peculiar construction, together 55 with the limited space for the application of ball-bearings thereto, and particularly at the points referred to and the cheapness with which such rufflers must be manufactured and sold, if at all. 60 Pivoted to the lower end of the needle-bar lever is the ruffler-blade carrier 16, (see Figs. 1, 2, 4, and 14,) provided with an upturned lug 17, secured to the ruffling-blade lever 8 by a pivot 18, and to the under side of which 65 is secured a ruffling-blade 19, the ruffling-

blade being preferably secured to its carrier 16 (see Figs. 12 and 13) by means of a bayonet-joint, and a fixed pin on the carrier adapted to register with, fit, and project through a hole in the ruffling-blade when the 70 bayonet-joint is closed. In other words, the ruffling-blade is provided with perforations 20, through and beyond which the head of a screw or headed pin 21 may freely pass, and with slots 22 opening therein of a diameter 75 conforming to the diameter of the shank of said screws or pins, which headed pins are fixed in the carrier with one of said pins so arranged as to pass through one corner of the ruffling-blade and the other at about the forward end of the carrier, a pin 23 on the carrier being so arranged that when the ruffling-blade is slipped over the headed pins and then pushed backward until the shanks of the headed pins have entered slot 22, so that the pin 23 will 80 register with a corresponding perforation 24 of the ruffling-blade and be forced therethrough by spring action of the ruffling-blade. When a ruffling-blade is thus secured to its carrier, it may be readily removed by springing it clear of the pin 23 and then drawing the blade forward until the headed pins register with the receiving-openings therefor in the blade, the advantage of this construction being that when the ruffling-blade becomes bent 85 or otherwise injured or worn it may be removed for repairs or for the substitution of a new one without injury to any of the parts of the ruffler and quickly and conveniently by the ordinary user of rufflers, whereas heretofore the ruffling-blades have been so attached to their carriers by rivets that an expert is required to remove them, and even then the ruffler is frequently injured and if not injured is frequently disfigured. 90 Directly over the ruffling-blade is the ruffling-guide 4, which is provided with a longitudinal slot 25, through which passes a headed screw or pin 26, secured to the ruffling-blade carrier, and which, together with the slot, constitutes means for guiding the ruffling-blade 100 in its reciprocations. The distance between the side walls of the slot 25 is slightly less than the diameter of the antifriction-ball 27, projecting partly therein and bearing against 105 the guide 4 of the ruffling-blade 19 in such a manner as to constitute an antifriction-bearing for the ruffling-blade in its reciprocations, and thereby substantially reduces the friction 110 thereof as compared with ruffling-blades or carriers thereof which have heretofore had a bearing directly against said guide. The advantage of an antifriction-roller between the ruffling-blade or its carrier and the guide is 115 not only that of reducing friction, but, more 120 important, that of dispensing with any necessity whatever of a lubricant at this point, and thereby any injury therefrom to the goods being ruffed, and the reduction of friction to a degree promoting the durability of the ruffler 130

and at one of the two points where the greatest wear occurs in a ruffler.

The ruffling-blade lever 8 has a forwardly-projecting arm 28, (see Figs. 1 and 2,) provided on its outer upper edge with an angular bend, forming a fixed stop 29 for and beneath the needle-bar lever 6.

A contact device operating between two fixed stops in a ruffler can only regulate lost motion, the limit of which is fixed by the distance between said fixed stops, and therefore not only the extreme length of the stroke of the ruffling-blade, but the location of the extreme length of said stroke between two fixed points relative to an immovable presser-foot, and in some instances a non-adjustable separating-blade, the result being that when the stroke of the needle-bar of a sewing-machine is higher than that for which such a ruffler 15 was made the ruffling-blade is carried forward of the shoulder of the presser-foot, and, on the other hand, when the downstroke of the needle-bar is lower than that for which the ruffler was made the ruffling-blade does 20 not advance far enough forward toward the shoulder to form a perfect ruffle or plait. Neither a ruffle nor a plait can be perfectly formed without the ruffling-blade stopping in its forward movement rearward of and at a 25 distance from the shoulder of the presser-foot corresponding to about the thickness of the fabric to be ruffled, for when it falls substantially short of this the ruffle or plait, as may be, is not perfectly formed nor in position to 30 be perfectly stitched, which latter is also a condition necessary for the production of a perfect ruffle, and, on the other hand, when the ruffling-blade passes forwardly beyond the shoulder of the presser-foot the ruffle formed 35 during the advanced movement of the blade is pulled out and distorted by the time the ruffling-blade reaches the limit of such a forward movement and further distorted by the withdrawal of the ruffling-blade from this advanced position rearward of the shoulder, and 40 in either event properly stitching is prevented. Again, in sewing-machines in which oscillating or rotary shuttles are employed the ruffling-blade should not move as far forward 45 to produce perfect work as in sewing-machines having reciprocating shuttles, for with oscillating or rotary machines if the ruffling-blade moves too far forward of the needle the tension of the thread will not draw the stitch 50 tight enough, but leave the stitch loose, the result of which is the imperfect stitching of the ruffle, whereas, on the other hand, with reciprocating-shuttle machines the ruffling-blade must pass farther forward of the point 55 of the needle to tighten the stitch, and one of the objects of my invention is to remove the objections referred to common to the employment of fixed stops and meet the requirements in sewing-machines the shuttles of 60 which are either oscillating, rotary, or reciprocating, and this by such an adjustment of one of the stops for the contact device as will under every condition of any of those sewing-machines provide for perfectly adjusting the ruffling-blade to the shoulder of the 65 presser-foot both for producing scant and full gathers and narrow and wide plaits. To these ends the needle-bar lever is also provided at about its upper end with a lug 30, to which by a pivot 31 is pivoted a movable and adjustable stop 32, which, like the fixed stop 29, is permanently in the path of movement of the needle-bar lever. The movable stop 32 is formed by a right-angle bend on a lever 33 and preferably a spring lever or arm, which projects downwardly across the arm 28 of the lower fixed stop 29 and is bent at 33^a (see Fig. 1) 70 around said arm, at which point a thumb-screw 33^b, passing through the arm and impinging against arm 28, operates to lock the lever 33 to 75 said arm, which is provided with gage-marks 34 (shown in Fig. 2) to determine the adjustment made of the movable stop. Both the fixed stop 29 and the movable stop 32 are adapted to be 80 engaged at will by the needle-bar lever and also 85 by a contact device 35, pivoted to the needle-bar lever 6 by a pivot 36 at a point between 90 said two stops, the contact device being provided with a lever or a handle 37 bent at its lower end around and so as to move on a segment-gage 38, formed on or secured to a portion 95 of the needle-bar lever projecting rearwardly from its pivot 5, a thumb-screw 39 serving to lock the lever 37, and with it the contact device, at any point upon the segment-gage. The movable stop by its angular form and the manner in which it is pivoted is so constructed that when its lever 33 100 is swung forwardly to position (shown in full lines in Fig. 2) the length of movement of the 105 needle-bar lever between the stops is the greatest, and when the lever 33 is swung rearwardly to the limit of its movement in that direction this length of movement is gradually decreased and is the shortest when the 110 lever is at the limit of its rearward movement, as indicated by the dotted lines in Fig. 2.

The contact device 35 is substantially triangular in form, so that when the lever 37 115 thereof is swung to its lowest position of the sector-gage 38 both the upper and lower edges of the contact device will lie parallel with the corresponding edges of the needle-bar lever. The width of the contact device 120 is such that in one position its edges do not project beyond the edges of the needle-bar lever, and when the contact device is in this position the upper stroke of the needle-bar lever, and therefore the length of its lost 125 motion, may be increased and decreased and the forward stroke of the blade be correspondingly increased and decreased by the adjustment of the contact device, as before described, within the range of movement of the 130

adjustable stop, and to this extent the limit of the forward stroke of the ruffling-blade is increased or diminished alone by the adjustment of the movable stop. The upper side 5 of the triangular contact device is longer than the lower side thereof, and the pivot of the contact device is located above a line drawn centrally through the base and point of the triangle, so that when the contact device is 10 swung to the position indicated by dotted lines in Fig. 1—that is to say, the lever of the contact device is swung to a position about midway the length of the sector-gage—the base of its triangle is moved upwardly in a 15 plane above the upper edge of the needle-bar lever, as indicated by said dotted lines, the result being that the length of lost motion of the needle-bar arm is correspondingly shortened without regard to the position of the 20 upper adjustable stop, but of course correspondingly decreased in shortness when the lever of the adjustable stop is swung rearward and likewise correspondingly increased as the lever of the adjustable stop is swung 25 forward. With the contact-point in the elevated position above the edge of the needle-bar arm, as just described and indicated in dotted lines in Fig. 1, and the adjustable stop is in its lowered position, as indicated by dotted 30 lines in the same figure, the ruffling-blade will be adjusted with reference to the needle to its minimum or shortest forward stroke, while at the same time it will make the full length of its rearward stroke, the successive 35 continuous movements of which strokes is necessary for the making of scantest gathers and narrowest plaits. If, however, the lever 37 of the contact device be moved to the upper end of the sector-gage, the elevated position 40 of the contact device above the edge of the needle-bar lever will not be changed, but the lower forward edge will be projected to the limit of its movement below the lower edge of the needle-bar lever, and as a result the ruff- 45 fling-blade will be moved to the limit of its backward stroke without changing the limit of its forward stroke last described, and from the foregoing it will be understood that the 50 adjustments of the movable stop and the contact device at varying points between the points specifically mentioned will vary the adjustment described in connection thereto to a relative degree. The extreme range of the 55 various adjustments of the contact device and the adjustable stop are only necessary for the perfect adjustment of a ruffler for the making of full and scant gathers and narrow and wide plaits in the absence of an adjustment of the presser-foot relative to the ruffling-blade and 60 the separating-blade—that is to say, only when the difference in the stroke of the needle-bars of sewing-machines is so great that the range of adjustment of the ruffler is insufficient without adjusting the presser-foot itself.

65 As a means providing for the adjustment

above referred to the presser-foot 39 of my invention (see Figs. 1, 2, and 10) is made separate from the presser-piece 3, secured to a lateral bar 40 (see Fig. 5) by rivets 41 41 or other means, which project between the presser-foot 70 and the presser-piece and forms a lateral extension of a longitudinally-adjustable sliding frame 42, mounted upon the ruffler-frame and having formed thereon a curved gage 43, in which is a circular opening receiving an eccentric 75 44, secured to the bed-plate 1 of the ruffler-frame (see Figs. 3, 4, and 5) by a pivot 45, the eccentric being secured to a lever 46 by rivets 45^a, the outer end of which lever is bent over the edge of the gage-plate 43, as 80 shown at 47, and adapted to be locked in whatever position it may have by a thumb-nut 48, (see Figs. 1, 3, 7, 8, and 14,) the eccentric 44 being clearly shown in Fig. 4, in which the lever is removed. By shifting the lever 46 85 the sliding frame 42 is moved longitudinally back and forth along the ruffler-frame, and by this means the presser-foot is adjusted longitudinally independent of the presser-piece and also longitudinally toward and away from the 90 ruffling-blade 19 and the needle-hole in the presser-piece.

Separating-blade 49 is secured by a rivet or rivets 50 or other suitable means (see Figs. 1, 2, 3, 4, 5, and 14) to a bar-support 51, bent upwardly and over the edge of the ruffling-frame, as shown at 52, and secured to the sliding frame 42 by means of a pin 53, secured to the ruffling-frame, which pin projects through a closed-end slot 54 in the sliding 100 frame 42 and into an open-end slot 55, formed in the bent end 52 of the separating-blade support 51. There is also an open-end slot 56 in the bent end 52 opposite the slot 55, through which passes a set-screw 57 into a sliding frame 42, and thereby securing the ruffling-blade to the sliding frame.

The sliding frame 42 (see Figs. 3 and 4) is provided at its forward end with an elongated slot 58, through which projects a headed bolt or screw 59 into the ruffler-frame, which with a slot serves to hold the sliding frame and the ruffling-frame together, and pin 53 and slot 54 at the opposite end serve to guide the sliding frame in its adjustment for simultaneously adjusting the separating-blade and the presser-foot with reference to the ruffling-blade.

The presser-piece 3 (see Figs. 3, 4, and 10) is provided with the usual needle-hole 60, the presser-foot 51 (see Fig. 10) being also provided with an elongated needle-hole 61, registering with the presser-piece needle-hole throughout the limit of the forward and backward adjustment of the presser-foot, which latter is also provided with a shoulder 62, 120 against which the ruffles or plaits are carried by the ruffling-blade in their formation. The elongation of the needle-hole 61 in the presser-foot provides for an extended range of adjusting of the presser-foot with reference to 130

both the needle-hole 60 of the presser-piece and the ruffling-blade and also the one independently of the other, with the result that a perfect ruffle or plait is not only perfectly formed, but perfectly stitched as to place and as to tension. The presser-foot, as shown in Fig. 10, also has a downward bend from the point at which it is attached to the lateral bar 40 to give it a spring action upon the fabric passing under it during the ruffling operation.

The ruffling-blade carrier 16 and the ruffling-blade support 51 (see Figs. 3, 4, 5, 9, 10, and 12) are respectively provided with the usual open-end guide-strip slots 69 and 70, through which may be introduced a ruffler piece or band, and guided thereby and secured to the presser-piece is an upper-strip-guide plate 71, (see Figs. 2, 3, 4, and 10,) provided with transverse slot 72, through which passes a set-screw 73, providing for the lateral adjustment of the plate 71, which has in its rear end an enlarged slot 74, closed at both ends and surrounding the needle-hole 60. The forward end of this guide-strip plate 71 projects under the ruffling-blade guide 4, (see Fig. 10,) and between said end a closed end slot 74 is provided with an open-end slot 75, (see Fig. 10,) which with closed-end slot forms a guide for an upper strip. The lateral adjustability of this upper-strip guide permits the adjustability of the strip lateral with reference to the ruffle or plait and also the location of the line of stitching relative to the edge of said strip. The range of the lateral adjustment of this strip-guide plate, as will be seen, will be sufficient for that purpose.

Having thus described my invention, what I claim, and desire to secure by Letters Patent, is—

1. In a ruffling device for sewing-machines, a needle-bar lever, a ruffling-blade lever, a pivot for said levers, and a ruffling-frame standard supporting said pivot in combination with ball-bearings interposed between said levers, and the supporting-standard, substantially as described.

2. In a ruffling device for sewing-machines, a needle-bar lever, a ruffling-blade lever, a pivot for said levers, and a ruffler-frame standard supporting said pivot in combination with a plate provided with a series of perforations interposed between said levers and the standard, and antifriction-balls seated in said series of perforations and bearing against said levers and standard, substantially as described.

3. In a ruffling device for sewing-machines, a ruffler-frame standard, a needle-bar lever and a ruffling-blade lever respectively arranged on opposite sides of said standard, a pivot common to both of said levers supported by said standard in combination with plates arranged upon each side of the standard next thereto and supported by said said pivot, and provided with a series of perforations, the

balls seated therein and against said levers and constituting antifriction-bearings therefor, substantially as described.

4. In a ruffling device for sewing-machines, a needle-bar lever and a ruffling-blade lever each provided with annular grooves, a pivot for said lever, a ruffling-frame standard supporting said pivot in combination with plates interposed between said levers and the standard, and provided with perforation at intervals, balls projecting into said perforations and the annular grooves in said levers and constituting ball-bearings for the levers, substantially as described.

5. In a ruffling device for sewing-machines, a ruffling-blade, means for operating the same, and a guide-plate therefor, in combination with a shifting-fulcrum for the ruffling-blade interposed between the guide-plate and said blade, substantially as described.

6. In a ruffling device for sewing-machines, a ruffling-blade, a ruffling-blade carrier and a ruffling-blade guide in combination with an antifriction-ball interposed between said carrier and guide and constituting an antifriction ball-bearing for the ruffling-blade, substantially as described.

7. In a ruffling device for sewing-machines, a ruffling-blade, means for operating said blade, and a guide-plate therefor provided with a longitudinal slot in combination with an antifriction-ball projecting in said slot and interposed between said guide-plate and the ruffling-blade, substantially as described.

8. In a ruffling device for sewing-machines, a ruffling-blade, means for operating said blade, and a guide-plate therefor provided with a longitudinal slot, a pin rigidly connected with the ruffling-blade, projecting into said slot and thereby serving to guide the movements of the blade in a straight line in combination with an antifriction-ball arranged between the ruffling-blade and said guide-plate and projecting in said slot, substantially as described.

9. In a ruffling device for sewing-machines, a ruffling-blade, a ruffling-blade lever, a needle-bar lever and means for operating the same, in combination with stops one of which is adjustable, a contact device and means to adjust said contact device to engage one of said stops to the exclusion of the other or to engage both of said stops, and to be disengaged from both of said stops, substantially as described.

10. In a ruffling device for sewing-machines, a ruffling-blade, a ruffling-blade lever, a needle-bar lever and means for operating the same, in combination with upper and lower stops, the upper one of which is adjustable, and a contact device and means to adjust said contact device to engage one of said stops to the exclusion of the other, or both of said stops, and to be disengaged from both stops, substantially as described.

11. In a ruffling device for sewing-machines, a ruffling-blade, a ruffling-blade lever, a needle-bar lever and means for operating the same, in combination with upper and lower stops, the upper one of which is adjustable, and a pivoted contact device adapted to be moved to engagement with the upper stop to the exclusion of the lower stop, or to engagement with both of said stops, and to be disengaged from contact with both of said stops, substantially as described. 60
12. In a ruffling device for sewing-machines, a ruffler-frame, a ruffling-blade, means for operating said blade, a presser-piece mounted on said frame and provided with a needle-hole, a sliding frame in combination with a presser-foot, and a separating-blade secured to said sliding frame and simultaneously adjustable with the presser-foot with reference to the needle-hole in the presser-piece, substantially as described. 65
13. In a ruffling device for sewing-machines, a ruffler-frame, a ruffling-blade, means for operating said blade, a presser-piece mounted on said frame and provided with a needle-hole, a sliding frame in combination with a presser-foot and a separating-blade secured to the sliding frame and simultaneously adjustable with reference to the needle-hole in the presser-piece and means for adjusting said presser-foot and separating-blade, substantially as described. 70
14. In a ruffling device for sewing-machines, a ruffler-frame, a ruffling-blade, means for operating said blade, a sliding frame, a presser-foot and separating-blade secured to said sliding frame in combination with an eccentric connection between the ruffling-frame and the sliding frame, for adjusting the latter and with it the presser-foot and separating-blade, substantially as described. 75
15. In a ruffling device for sewing-machines, a ruffler-frame, a ruffling-blade, means for operating said blade, a sliding frame provided with an eccentric bearing-surface, a presser-foot supported by the sliding frame, in combination with an eccentric pivoted to the ruffling-frame and engaging said bearing-surface and means for adjusting said eccentric and with it the sliding frame and presser-foot, substantially as described. 80
16. In a ruffling device for sewing-machines, a ruffler-frame, a ruffling-blade, means for operating said blade, and an eccentric pivoted thereto in combination with a presser-foot, a sliding frame, a bearing for said eccentric, whereby the presser-foot and sliding frame are adjusted upon the ruffling-frame, a gage upon the sliding frame, a lever secured to the eccentric and coöperating with said gage to indicate the degree of adjustment of the sliding frame, and means for locking said lever to the sliding frame in its various positions upon the gage, substantially as described. 85
17. In a ruffling device for sewing-machines, a ruffler-frame, a ruffling-blade and means for operating said blade, in combination with a sliding frame provided with elongated slots toward opposite ends thereof, a set-screw passing through one of said slots into the ruffler-frame, and a pin in the ruffler-frame projecting through the other of said slots whereby the sliding frame is secured to and adjustable upon the ruffler-frame in a straight line, and a presser-foot and separating-blade secured to and simultaneously movable with the sliding frame, substantially as and for the purpose described. 90
18. In a ruffling device for sewing-machines, the ruffler-frame, a ruffling-blade and means for operating said blade, the needle-bar lever and the ruffling-blade lever pivoted thereto a contact device pivoted to the needle-bar lever, stops upon the ruffling-blade lever, means for adjusting one of said stops and the contact device with reference to the needle-bar lever and to each other, a presser-piece provided with a needle-hole mounted upon the ruffler-frame, in combination with a sliding frame, a presser-foot and a separating-blade secured thereto and means for simultaneously adjusting said presser-foot and separating-blade to each of the several various adjustments of the ruffling-blade, substantially as described. 95
19. In a ruffler, a ruffling-blade, a separating-blade and means for operating and adjusting said blades with reference to the needle-hole in combination with a presser-piece provided with a needle-hole, a presser-foot simultaneously adjustable with the separating-blade and having an elongated needle-hole providing a needle-passage in the presser-foot registering with the needle-hole in the presser-piece throughout the adjustment of the presser-foot, substantially as described. 100
20. In a ruffling device for sewing-machines, a ruffling-blade, and a carrier therefor in combination with a bayonet-joint connecting said blade and carrier, a perforation and an opposing pin adapted to fit, register with and project into said perforation and lock the bayonet-joint in a closed position, substantially as and for the purpose described. 105
